UNITED STATES PATENT OFFICE.

AUGUST KEHM, OF CHICAGO, ILLINOIS.

RADIATOR.

Application filed November 8, 1920. Serial No. 422,632.

To all whom it may concern:

Be it known that I, AUGUST KEHM, a citizen of the United States, and resident of Chicago, county of Cook, and State of Illinois, have invented certain new and useful Improvements in Radiators, of which the following is a specification and which are illustrated in the accompanying drawings, forming a part thereof.

10 The invention relates to radiators and has for its object to provide a radiator of increased efficiency with a view to reducing the weight and fluid contents in proportion to heating capacity. While it has been recognized that the mounting of radiators in up-right position is desirable to secure rapid movement of the surrounding air over the heating surfaces of the radiator, it is also known that the advantages of this arrangement are only partially obtained in practice because of the fact that air which is warmed by contact with the lower portions of the radiator does not rise in close proximity to the heating surface throughout the full 25 height of the radiator, but moves upwardly and outwardly away from the radiator in the intermediate portions of the same.

The present invention accordingly contemplates an upright radiator having vertical flues which preferably extend throughout the major portion of the height of the radiator and which serve to receive and confine a substantial part of the air rising about the radiator. Contact of the air so confined 25 with the heating surface of the radiator throughout the full length of the flues is thereby insured with the result that warm air is discharged from the flues into the room at both a high temperature and high 40 velocity. Furthermore, as the movement of air over the heating surface is stimulated by the vertical arrangement of the flues, the radiator becomes more efficient and both the heating surface and fluid contents may be 45 reduced.

In the accompanying drawings;—

Fig. 1 is a detail side elevation of a radiator embodying the features of improvement provided by the invention; 50 Fig. 2 is an end view of the same partly broken away and with one of the radiator columns removed and the top and bottom headers shown in section, and

55 Fig. 3 is a plan sectional view taken on the line 3—3 of Fig. 2.

The invention is illustrated as applied to a wall radiator of the type forming the subject of my patent on radiator, No. 1,383,724, granted July 5, 1921, the same comprising top and bottom headers 10, 11, and upright 60 columns 12 connecting the headers. In this particular type of wall radiator the columns 12 each have one straight side 13 which lies in the same plane with the adjacent side of the headers and an offset side 14 which projects beyond the headers. 65

In carrying out the present invention the columns 12 are preferably less numerous than is usual in radiators of similar size. The drawings show the columns 12 arranged 70 along the headers 10, 11, with relatively wide spaces 15 between adjacent columns. Since the chambers, as 16 (Fig. 3) of the columns 12 provide the principal part of the fluid capacity of the radiator while the walls of 75 the columns represent an important part of the weight of the radiator, the reduction of the number of columns affords a substantial reduction in both the fluid capacity and the weight of the radiator. 80

On the other hand the relatively wide spacing of the columns 12 provides room between the columns for vertical flues 17. As shown, the lower ends of these flues are located just far enough above the bottom 85 header 11 of the radiator to provide a free opening for the entrance of air into the flues while the upper ends of the flues are located only a short distance below the top header 10. Air entering the spaces 15 between the 90 columns 12 at the bottom of the radiator is accordingly confined in its upward travel until it reaches the top of the radiator where it is discharged into the room at relatively high velocity. 95

In order that the walls of the flues 17 may constitute a part of the heating surface of the radiator they are preferably constructed to make contact with the walls of the adjacent columns 12 at each side over a substantial area. In the construction illustrated this is accomplished by forming the flues 17 from sheet metal and of such size that elastic distortion of the flues is required for their introduction between the columns. 100 Under these circumstances, each flue 17 is forced between two adjacent columns 12 and makes a wide contact with the column at each side throughout the length of the flue, as at 18 and 19 (Fig. 3). Furthermore, 110

each flue is held in place by the elastic expansion of its walls and fastening devices are not required.

As the walls of the flues 17 are heated by contact with the adjacent columns 12 they serve to raise the temperature of the air rising within the columns and thus stimulate its upward movement. The lesser effectiveness of these walls as heating surface, as compared with the walls of the columns 12, is accordingly largely offset by the movement of air over the inside surface of the flues at high velocity. The exterior surface of the flues 17 is exposed to air rising about the radiator in like manner with the columns 12 and is also to be regarded as a part of the heating surface of the radiator.

While the employment of the particular style of wall radiator illustrated in the drawings is not essential, its use is advantageous as it permits of the extension of the flues 17 in front of the upper header 10. The discharge of heated air from the upper ends of the flues is thus largely directed outwardly into the room as indicated by the arrows at the upper part of Fig. 2.

When the columns 12 and headers 10, 11 are of cast iron, as shown, the sheet metal flues 17 are conveniently applied after the cast iron portions of the radiator have been erected at the place of use.

Under the circumstances the elastic expansion of the walls of the flues against the adjacent columns may be supplemental, if desired, to avoid accidental displacement of the flues and insure good contact of the walls of the flues with the heating columns, by the introduction of clamping screws 20 through the flues for compressing the walls of the flues in the direction of the depth of the radiator. These clamping screws may be as numerous as required in accordance with the height of the radiator and the stiffness of the walls of the flues, each flue being provided with two such clamping screws in the particular construction illustrated in the drawing. As the employment of the said clamping screws tends to increase

both the force with which the walls of the flues are pressed against the heating columns and the area of contact between these parts, their use is especially important in securing a better conduction of heat to the walls of the flues.

I claim as my invention:

1. In a radiator, in combination, a plurality of upright parallel heating columns and upright flues open at top and bottom located between the columns, the walls of the flues being independent of but contiguous with those of the columns.

2. In a radiator, in combination, a plurality of upright parallel heating columns, and upright flues having continuous walls located between the columns, the ends of the flues being open and the walls of each flue being in contact with both of the two adjacent heating columns throughout the length of the flue, but terminating short of the ends of the heating columns.

3. In a radiator, the combination of a plurality of upright heating columns and flues arranged alternately and with their adjacent walls held in close contact over large areas, said flues being tubular and having wide openings to permit free passage of air therethrough.

4. In a radiator, in combination, a plurality of upright parallel heating columns and upright flues having elastically expandable walls located between the columns, the ends of the flues being open and the two sides of each flue being held in contact with the adjacent heating columns by elastic expansion of the walls of the flue.

5. In a radiator, in combination, a plurality of parallel upright heating columns and upright flues having continuous flexible walls located between the columns, the ends of the flues being open, and spreading means acting on the walls of the flues to hold them in contact with adjacent heating columns comprising clamping means compressing the flues in a direction perpendicular to the plane of the columns.

AUGUST KEHM.
